UNITED STATES PATENT OFFICE

120,755

DESIGN FOR A MEMORIAL GRAVE MARKER

Otto H. Harer, Painesville, Ohio

Application December 21, 1939, Serial No. 89,081

Term of patent 14 years

To all whom it may concern:

Be it known that I, Otto H. Harer, a citizen of the United States, residing at Painesville, in the county of Lake, State of Ohio, have invented a new, original, and ornamental Design for a Memorial Grave Marker, of which the following is a specification, reference being had to the accompanying drawing, forming part thereof.

In the drawing,

Fig. 1 is a top plan view of a memorial grave marker, partly illustrated in dotted lines, showing my new design, it being understood that the ornamentation shown forms a continuous border completely surrounding the article.

Fig. 2 is a view taken on line 2—2 of Fig. 1.

I claim:

The ornamental design for a memorial grave marker, as shown and described.

OTTO H. HARER.
